UNITED STATES PATENT OFFICE.

ALBEN E. LUNDELL, OF NEW YORK, N. Y., ASSIGNOR TO WESTERN ELECTRIC COMPANY,
INCORPORATED, OF NEW YORK, N. Y., A CORPORATION OF NEW YORK.

TELEPHONE METERING SYSTEM.

1,243,314.

Specification of Letters Patent. Patented Oct. 16, 1917.

Application filed January 14, 1916. Serial No. 72,148.

To all whom it may concern:

Be it known that I, ALBEN E. LUNDELL, a citizen of the United States, residing at New York, in the county of Bronx and State 5 of New York, have invented certain new and useful Improvements in Telephone Metering Systems, of which the following is a full, clear, concise, and exact description.

This invention relates to toll devices, and 10 the operating means therefor employed in automatic telephone systems. While, in the present embodiment of the invention, a full automatic system is disclosed, it is to be understood that the features of the invention 15 are equally applicable to a semi-automatic system.

One of the principal features of the invention resides in the provision of means common to a plurality or group of cord circuits 20 for controlling the message register of any calling line which has a completed connection extending through one of the cord circuits of the group, irrespective of whether such calling line is a direct or a regular subscriber's line, or is a private branch exchange line.

Another feature of the invention resides in the provision in an automatic or semi-automatic telephone system of means such 30 that when a non-register station, as, for instance, the information operator at the exchange, is called, the message register will not be operated.

A further feature of the invention resides 35 in the provision of means for controlling the operation of the coin-collect device which, if desired, may be associated with lines supplied with message registers and means for controlling said coin-collect device to refund 40 the coin deposited upon a non-completed call or upon a call to a non-register or non-pay station, as before referred to.

In the drawings, Figures 1, 2 and 3, in order, with Fig. 1 at the left, show a portion 45 of the circuits and diagrammatically indicate the apparatus employed in establishing a connection in an automatic telephone exchange. The devices shown in Figs. 4, 5 and 6 are the message register or coin collect 50 controlling apparatus which is common to the cord circuits. These three figures represent modifications of the message register controlling device, and may be interchangeably placed above Fig. 2.

55 The message register, shown associated

with the upper line in Fig. 1, may be of any desired character, the only requisite being that its operating magnet has a low resistance winding and a high resistance winding connected in the circuit in a manner 60 similar to that shown in the drawing.

The coin-collect device, shown associated with the substation at the right in Fig. 1, may be of any desired character, the only requisite being that it is provided with a 65 polarized operating magnet and has contacts so arranged that it is necessary to deposit a coin therein in order to cause the operation of the line relay.

The line-finding switch may be of any 70 suitable character and as it forms no part of the present invention it is only diagrammatically indicated in the drawing. If desired, the line-finding apparatus may be of the character disclosed in applicant's co-pending applications, Serial No. 16,357, filed March 23, 1915, and Serial No. 15,437, filed March 19, 1915. 75

The switches, indicated in Figs. 2 and 3 of the drawings, may be of a character similar to that shown in Patent 1,123,696. 80

The sequence switch, of which the contacts and operating means are diagrammatically illustrated in Fig. 2, may be of the type shown in Patent 1,127,808. 85

The power means or driving device of the rotary switching apparatus, shown in Figs. 4, 5 and 6, may be of the same character as the driving means for the sequence switch of said patent, and, if desired, sequence 90 switch structures may be substituted for the switching devices shown in these figures.

It is believed that this invention is of such a character as to be readily understood from a description of the operation of the toll devices under various circumstances without further detailed description of the apparatus employed. We will now assume that the subscriber shown at the left in Fig. 1 has established a connection through the line 100 switch 1, the selector switches 2, 3 and 4 and the connector switch 5, to the subscriber shown in the upper right corner of Fig. 3, these switches being operated in any known desired manner. In the present embodiment 105 of the invention, at the time the talking connection is established the sequence switch 6 (Fig. 2) will be in a position 13, and will remain in this position until the calling subscriber replaces his receiver on the hook. 110

With the sequence switch in position 13, a circuit will be completed from battery through the supervisory or cord relay 7, through the switches and trunks to the called subscriber's line, over the lower side of said line, through the substation apparatus thereat, back over the upper side of said line, through the upper brushes of the switches and back to battery through sequence switch contact 9. Relay 7 will be energized and complete a circuit for relay 10, which in attracting its right armature, completes a holding circuit for itself through sequence switch contact 11. The attraction of the inner right armature of relay 10 connects sequence switch contact 12 to ground.

Upon the termination of the conversation, when the calling subscriber places his receiver on the hook, the supervisory relay 13, which is in the calling subscriber's battery supply circuit and therefore energized, will be deenergized, opening the circuit for relay 14, which in retracting its armature, completes a circuit from battery through the motor magnet of sequence switch 6, sequence switch spring 15 and its lower contact, and back contact and armature of relay 14 to ground. The sequence switch motor magnet is energized and moves the sequence switch into position 14.

We will first consider the operation with the controlling device shown in Fig. 4 associated with the connecting circuit of Fig. 2. As both contacts of sequence switch spring 12 are now closed, a circuit is completed from battery through relay 16, upper sequence switch contact 12 to the front contact and inner right armature of relay 10.

The mechanism shown within the dotted rectangle in Fig. 4 is a message register controlling device allotter, and, as will hereinafter appear, the brushes thereof, when at rest always test upon contacts associated with an idle controlling device. One of the controlling devices comprises the mechanism and circuits appearing above and at the left of said dotted rectangle. Each of the pairs of contacts of this allotter would represent the terminals of conductors extending to a similar controlling device.

Now upon the energization of relay 16, a circuit will be completed from battery, through the motor magnet 17 of the idle preselected register controller cord finder, to the back contact and right armature of the marginal relay 19, the outer brush of the allotter 20, the contact and armature of relay 16 to ground. The brushes of the cord finder 18 are thereupon rotated, and when they engage the contacts associated with the trunk through which the connection was established, a circuit will be completed from battery through relay 19, the innermost brush of the cord finder 18, resistance 21, lower sequence switch contact 12 and the

contact and inner right armature of relay 10 to ground. Relay 19 is energized and opens the circuit for the motor magnet 17, thus stopping the cord finder, in association with the desired trunk.

It may be here noted that if the calling line is a regular subscriber's line, the third conductor thereof will be connected directly to ground through the cutoff relay 22 and the windings of the register operating magnet 23 in parallel. However, if the calling line is a private branch exchange line, this third conductor will be similarly connected to ground, but through a 48-volt battery. This alternative arrangement is indicated in Fig. 1 of the drawings by the broken connection of the two leads, one extending directly to ground and the other through battery to ground.

When the cord finder 18 stops on the cord circuit through which the connection is about to be disestablished, a plurality of circuits are completed as follows: first, from battery through the left armature and contact of relay 24 (Fig. 4), the left winding of marginal relay 25, the left or high resistance winding of relay 26, outermost armature and contact of relay 27, the outermost brush of cord finder 18, sequence switch contact 28, through the switch brush, over the conductor associated therewith to ground, through the cutoff relay 22 and winding of the magnet 23.

We will first assume that the calling line is a regular subscriber's line and that this circuit extends directly to ground through the magnets 22 and 23, in which case relay 26 will be energized, and by the attraction of its right armature will complete a low resistance shunt through its low resistance right winding about its high resistance left winding. This will permit an increased flow of current through the windings of the register magnet 23, causing it to attract its armature and thus register a call. The attraction of the armature of the message register also operates to short-circuit the high resistance right winding of said magnet, thus causing a further increased flow of current over the circuit previously traced. This will cause the energization of the marginal relay 25, which, in attracting its armature, will complete a circuit from ground through its armature and contact, the middle brush of the cord finder 18, sequence switch contact 28', through the down-drive motor magnet 29 of the selector switch shown at the right in Fig. 2, to battery and ground. This will cause the release of the selector switch 2 and its return to normal, in a manner such as disclosed in Patent 1,103,623.

As the selector switch approaches its normal position, the commutator brush 30 thereof engages the conducting segment 31, completing a circuit from ground through sequence switch contact 32 and the motor

magnet of sequence switch 6 to battery and ground; thus moving the sequence switch to position 15. In position 15, a circuit is completed from battery through the motor magnet 33 of the line finder switch shown at the left in Fig. 1, to sequence switch contact 15 and the back contact and armature of relay 14 to ground, thus causing the line finder to return to normal position. As the line finder approaches its normal position, the commutator brush 34 thereof engages the conducting segment 35, completing a circuit from ground through left sequence switch contact 32 and the motor magnet of sequence switch 6 to battery and ground, thus moving the sequence switch out of position 15 and to its normal or subnormal position, as desired.

At the time relay 27 operated in response to the operation of the stop relay 19, a circuit was completed from battery through the left armature of relay 24, the left winding of relay 25, the left winding of relay 26, both armatures of relay 27 and their contacts, the left winding of relay 24, the right winding of relay 25 and the left armature of relay 26 to ground. However, on account of the high resistance in this circuit, relay 24 will not operate due to the current flow therein.

Assuming now that the calling line is a private branch exchange line, in which case battery will be connected between cutoff relay 22 and the register magnet 23 and ground, then a circuit will be completed from grounded battery through the windings of the cutoff relay and magnet 23 in parallel, the line finder contact and brush, upper sequence switch contact 28, the outermost brush of cord finder 18, contact and inner armature of relay 27, left winding of relay 24, right winding of relay 25, and contact and left armature of relay 26 to ground. The current flowing in this circuit is assisted by the current flowing in the circuit just previously traced, and is sufficient to cause the energization of relay 24, which, in attracting its armatures, interrupts the circuit for relay 26 and at its right armature completes a short circuit through its low resistance winding around the high resistance winding of this relay; thus so reducing the resistance of the circuit as to cause the operation of the register magnet 23. Magnet 23, in attracting its armature as before described, short-circuits its high resistance winding, causing an increased flow of current over the circuits to cause the operation of the marginal relay 25, which in attracting its armature causes the return to normal of the selector switch and the line finder switch, in the manner previously described.

We will next consider the case in which the connection is extended to a non-pay station, such as shown at the lower right corner of Fig. 3. In this case, when the connection

is completed, the condenser 36 will be included in circuit with the cord relay 7, and the cord relay will therefore not operate. In the circuit as here shown, the talking current for the called subscriber is supplied through the impedance coil 37, contact and armature of relay 38, the substation talking set, over the upper side of the line and the upper conductor of the several trunks to ground through the upper right winding of the induction coil in the trunk circuit, Fig. 2. The circuit for the relay 38 extends from battery or ground, depending on whether the called station is a regular line or a private branch exchange line, thence through cutoff relay 39, relay 38, through the contact and sleeve brush of the connector switch, to grounded battery through sequence switch contact 40. As the battery connected to the sequence switch contact 40 is of 24-volt potential and the battery associated with the cutoff relay of the private branch exchange line is of 48-volt potential, relays 39 and 38 will be operated whether relay 39 is connected to the 48-volt private branch exchange battery or to ground.

As the relay 7 did not operate on a non-pay call, the circuit for relay 10 was not completed, and therefore ground is not connected to the sequence switch contact 12. Now when the calling subscriber replaces his receiver on the hook, the sequence switch 6 moves to position 14 as before, but the register control device will not be actuated, due to the non-operation of relay 10. As the sequence switch moves to position 14, contact 28' is closed, completing a circuit from battery through the down-drive clutch magnet 29 of the selector switch 2, contact 28', outermost right armature and back contact of relay 10, and sequence switch contact 11 to ground. This causes the return of the selector switch to normal, and the return of the finder switch occurs in the same manner as previously described.

We will next consider the coin-collect device 42 shown in Fig. 1. This may be associated with a regular line or a private branch exchange line either of which may be provided with a message register or not, as desired. It will be noted that the circuit of the line relay 49' is controlled by the contacts bridged by the coin 47, the upper conductor of the subscriber's line being grounded through said contacts and coin instead of through contacts of the cutoff relay as at the subscriber's line shown at the left in Fig. 1. As previously described when a successful connection is established to a regular line, the cord relay 7 is energized, in turn causing the energization of relay 10. Now when a calling subscriber whose station is provided with a coin-collect device, replaces his receiver on its hook after a connection of the character just described, a cir-

cuit is completed from the positive pole of the battery through resistance 43, relay 44, front contact and left armature of relay 10, lower sequence switch contact 45, the right 5 switch brush, the upper talking conductor of the subscriber's line, through the polarized magnet 46 of the coin-collect device, through the deposited coin 47 and the contacts engaged thereby to ground. This will cause 10 the actuation of the coin-collect device in a well-known manner to cause the deposit of the coin.

Upon an unsuccessful connection, or upon 15 a connection extended to a non-pay station, as the one shown at the lower right corner of Fig. 3, relay 7 will not have been energized and, therefore, relay 10 will have remained deenergized. Now when the calling 20 subscriber replaces the receiver upon the hook, a circuit will be completed from the negative pole of the battery through resistance 48, back contact and left armature of relay 10, sequence switch contact 45 to ground through the polarized magnet 46 of 25 the coin-collect device, as before. As the current now flowing through this circuit is of the opposite polarity to that furnished through the front contact of relay 10, the coin-collect device will now be operated in 30 such a manner as to refund the coin.

When a successful connection is established to a line having a toll device but no message register, the right armature of relay 10 will have been attracted, thus holding 35 the return circuit for the selector switch 2 open; and in the case assumed, insufficient current will flow through the cutoff relay 49 to cause the actuation of the marginal relay 25. Thus the circuit for the return mag- 40 net of the selector switch 2 will not be closed at the armature and contact of relay 25 as was previously the case. The relay 44 now being energized, will complete the circuit for the down-drive magnet 29 through its 45 armature and contact, when the restoration of the selector switch 2 and the finder switch 1 will occur in exactly the same manner as previously described.

In the message register controlling structure shown in Fig. 4, a plurality of said controllers would be provided, the allotter 20 operating at all times when at rest to maintain an operative circuit direct to an idle controlling device. Assuming now that the 50 brushes of the allotter 20 are on the contacts individual to an idle register controlling apparatus and that a successful call is disestablished. This will cause the energization of relay 16, which will complete 55 the circuit for the motor magnet 17 of the cord finder 18, as before described. When the cord finder engages the contacts of the desired trunk circuit, relay 19 will be energized and a circuit will be completed from bat- 60 tery through the motor magnet of the al-

lotter 20, the inner brush of the allotter, the front contact and right armature of relay 19, the outer brush of the allotter, to ground through the armature of relay 16. This will cause the allotter to move from set to set 70 of the contacts individual to the register controlling apparatus. The allotter 20 will continue to rotate until its brushes engage the contacts individual to an idle register controller. As the contacts of the second 75 register controller may be engaged by the allotter, before the trunk sequence switch has moved out of position 14, a second cord finder, corresponding to 18, may be started into operation, but on account of the marginal character of stop relays 19, the relay 19 of the second cord finder will not operate when the brushes of its cord finder 18 engage the contacts individual to the trunk through which the connection is being dis- 80 established.

We will now describe the modifications of the register controlling apparatus shown in Figs. 5 and 6 of the drawing. Either of these may be substituted for the mechanism 90 shown in Fig. 4. Fig. 5 discloses merely a cord finder for a single controlling apparatus. The lead extending from the upper contact of sequence switch spring 12, is carried directly to the right armature of relay 95 19', which corresponds in every way to the relay 19 shown in Fig. 4, except that it need not be marginal. The rest of the apparatus shown in Fig. 4 as being connected to the two outer brushes of the cord finder 18, will 100 be duplicated in Fig. 5 in connection with the brushes of the cord finder 18'.

Now when a call is disestablished and the connecting circuit sequence switch goes to position 14, a circuit will be completed from battery through motor magnet 17', back contact and right armature of relay 19', upper sequence switch contact 12, and front contact and inner right armature of relay 10 to ground. This will cause the cord 110 finder 18 to move from trunk to trunk until its brushes engage the contacts individual to the trunk through which the call is being disestablished, when a circuit will be completed for relay 19'. Relay 19' in 115 attracting its armature, will interrupt at its right armature the circuit for the motor magnet 17', and the operation of the left armature of relay 19' will cause the operation of the message register controller apparatus in exactly the same manner as described in connection with the mechanism shown in Fig. 4. As the process of registering a call and releasing the controlling device will occupy only a very brief interval 120 of time, a single controlling device may often be found to be sufficient.

In the modification shown in Fig. 6, an extended starter wire is provided for associating an idle message register controller 130

with a trunk through which a call is being disestablished. In this modification, the starter wire, which extends through the right armatures and contacts of the relays 5 19", is substituted for the allotter shown in Fig. 4. Each cord finder 18" of Fig. 6 will have associated therewith a register controlling mechanism exactly identical with that associated with the cord finder 18 of Fig. 4. The operation of the modification shown in Fig. 6 is as follows: When the cord finder sequence switch goes to position 14, a circuit will be completed from battery through the motor magnet 17" of the cord 10 finder of the idle controlling mechanism, through the back contact and right armature of relay 19" associated therewith, the upper sequence switch contact 12, to ground through the front contact and inner right 15 armature of relay 10. This will cause the operation of the cord finder 18" in a manner similar to that described in connection with cord finders 18 and 18'. When the cord finder engages the contacts associated with 20 the trunk, through which a connection is being disestablished, relay 19" will be operated and at its back contact will interrupt the circuit for the motor magnet 17", and at its front contact will extend the circuit to the 25 next cord finder 18', the relay 19" of which is retracted, that is, to the cord finder of the next idle controlling mechanism. This second cord finder may also be started into operation, but as the relay 19" is made marginal, it will not attract its armature, and therefore the operation of the second cord 30 finder will be without effect.

It is obvious that many modifications may be made in the details of this invention 40 without departing from the spirit thereof, and it is therefore understood that the scope of the invention is to be limited merely by the appended claims.

What is claimed is:

45 1. In a telephone system, a plurality of subscribers' lines, connecting circuits and switches for establishing a talking connection from one of said lines to another, toll apparatus associated with said lines respectively, controlling means for governing the operation of said toll apparatus, and means for automatically associating said governing means with any one of a group of connecting circuits used in establishing said 50 connection in order to govern the operation of the toll device of the calling subscriber.

2. In an automatic telephone system, subscribers' lines, automatic switches and connecting circuits for establishing a talking 55 connection from one of said lines to another, toll means associated with said lines respectively, a plurality of controlling devices, any one of which may be employed to selectively control the operation of said toll devices, and means for automatically associating an

idle one of said controlling devices with a connecting circuit used in establishing said connection.

3. In a telephone exchange system, regular subscribers' lines and private branch exchange lines, toll devices associated with each of said lines respectively, automatic switches for extending a talking connection from one of said lines to another, controlling means for selectively governing the operation of the toll device of calling lines irrespective of whether said lines are regular lines or private branch exchange lines, and means for automatically associating said controlling means with any one of a group of cord circuits used in establishing said connection. 75

4. In a telephone exchange system, subscribers' lines, a message register associated with each of said lines respectively, automatic switches for extending a connection from one of said lines to another, a controlling device for determining the operation or non-operation of the message register of a calling line, and means for associating said controlling device with any one of a group of connecting circuits used in setting up said connection. 80 85

5. In a telephone system, a plurality of subscribers' lines, automatic switches for establishing a talking connection from one of said lines to another, toll apparatus associated with said lines respectively, controlling means for governing the operation or non-operation of said toll apparatus, and a connecting circuit finder switch for automatically associating said governing means with any one of a group of connecting circuits used in establishing said connection in order to govern the operation of the toll 90 95 device of the calling subscriber. 100

6. In an automatic telephone system, subscribers' lines, automatic switches for establishing a talking connection from one of said lines to another, message registers associated with said lines respectively, a plurality of controlling devices, any one of which may be employed to selectively control the operation of said message registers, connecting circuit finder switches for said controlling devices respectively, and means for automatically causing a finder switch to associate an idle one of said controlling devices with any one of a group of connecting circuits used in establishing said connection. 110 115

7. In a telephone exchange system, regular subscribers' lines and private branch exchange lines, message registers associated with said lines respectively, automatic switches for extending a talking connection from one of said lines to another, a plurality of controlling devices common to a group of connecting circuits which may be used in establishing a connection, and means for automatically associating an idle control- 125 130

ling device with any connecting circuit used in establishing said connection to selectively govern the operation of the message register of the calling line irrespective of whether 5 said line is a regular line or a private branch exchange line.

8. In a telephone exchange system, subscribers' lines, message registers, one being associated with each of said lines, automatic

10 switches for extending a connection from one of said lines to another, a controlling device for determining the operation or non-operation of a message register of a calling line, and means responsive to the opening 15 of the hookswitch of the calling subscriber for automatically associating said controlling device with any one of a group of connecting circuits used in setting up said connection.

20 9. In a telephone system, a plurality of subscribers' lines, automatic switches for establishing talking connections from one of said lines to another, toll apparatus associated with said lines respectively, controlling 25 means for governing the operation or non-operation of said toll apparatus, a connecting circuit finder switch, and means automatically actuated incident to the opening of the hookswitch of the calling subscriber, 30 for causing said finder switch to associate said governing means with a connecting circuit used in establishing said connection in order to govern the operation of the toll device of the calling subscriber.

35 10. In an automatic telephone system, subscribers' lines, automatic switches for establishing a talking connection from one of said lines to another, toll devices associated with said lines respectively, a plurality of 40 controlling devices, any one of which may be employed to selectively control the operation of said toll devices, and means automatically responsive to the opening of the hookswitch of the calling subscriber subsequent 45 to the establishment of a completed connection for associating an idle one of said controlling devices with a connecting circuit used in establishing said connection.

50 11. In a telephone exchange system, regular subscribers' lines and private branch exchange lines, toll devices associated with each of said lines respectively, connecting circuits and switches for extending a talking connection from one of said lines to another, 55 controlling means for selectively governing the operation of the toll device of calling lines irrespective of whether said lines are regular lines or private branch exchange lines, and means for automatically associating a controlling device with a connecting circuit used in establishing said connection.

60 12. In a telephone exchange system, a calling subscriber's line, other subscribers' lines of different characters, connecting circuits and switches for establishing a connec- 65

tion from said calling line to any of said other lines, a toll device associated with said calling line, means common to a group of connecting circuits for operating said toll device when a connection is established from 70 said calling line to another line of one character, and means for preventing the operation of said toll device when a connection is established to a line of another character.

75 13. In a telephone exchange system, a calling subscriber's line, other subscribers' lines of different characters, connecting circuits and switches for establishing a connection from said calling line to any of said other lines, a toll device associated with said calling line, a controlling device for governing the operations of said toll device, means for associating said controlling device with any connecting circuit of a group 80 used in establishing said connection, means whereby said controlling device will cause the operation of the toll device when a connection is established from said calling line to another line of a certain character, and means for preventing said controlling means 85 from causing the operation of said toll device when a connection is extended to a line of a different character.

90 14. In a telephone exchange system, calling subscribers' lines, other subscribers' lines of different characters, connecting circuits and switches for establishing connections from said calling lines to said other lines, message registers associated with said calling lines respectively, a register controlling 95 device, means for joining said controlling device to any completed connection in order to control the operation of the message register of the calling line, means whereby said controlling device will cause the operation 100 of the message register of the calling line when a call is extended to a line of one character, and means whereby it will be prevented from causing such operation when a connection is extended to a line of a different character.

105 15. In a telephone exchange system, calling subscribers' lines, other subscribers' lines of different characters, connecting circuits and switches for establishing connections from said calling lines to said other lines, message registers associated with said calling lines respectively, register controlling devices, any one of which may be used to control the operation of the message register 110 of the calling line, and means whereby said controlling device will cause the operation of said message register when a connection is extended to a line of one character and for preventing said controlling device from 115 causing the operation of the message register when a connection is extended to a line of a different character.

120 16. In a telephone exchange system, a calling subscriber's line, other subscribers' lines 125

- of different characters, connecting circuits and switches for establishing a connection from said calling line to any of said other lines, a message register associated with said calling line, a controlling device for governing the operation of said message register, a finder switch for associating said controlling device with the calling line to cause the operation of said message register when a connection is established from said calling line to another line of one character, and means for preventing the operation of said finder switch when a connection is established to a line of another character.
17. In a telephone exchange system, a calling subscriber's line, other subscribers' lines of different characters, connecting circuits and switches for establishing a connection from said calling line to any of said other lines, a toll device associated with said calling line, means for associating said controlling means with any connecting circuit of a group used in establishing said connection to cause the operation of the toll device when a connection is established from said calling line to another line of a certain character, and means for preventing the association of said controlling means with said connecting circuit when a connection is extended to a line of a different character.
18. In a telephone exchange system, a group of calling lines, other subscribers' lines of different characters, connecting circuits and switches for establishing a connection from any of said calling lines to any of said other lines, toll devices associated with said calling lines respectively means common to the lines of the exchanges for operating the toll device of any calling line when a connection is established therefrom to an other line of one character, and means for preventing the operation of said toll device when the connection is established to a line of a different character.
19. In a telephone exchange system, calling subscribers' lines, other subscribers' lines of different characters, connecting circuits and switches for establishing connections from said calling lines to said other lines, message registers associated with said calling lines respectively, a register controlling device, a connecting circuit finder switch for joining said controlling device to completed connection in order to cause the operation of the message register of the calling line when a call is extended to a line of one character, and means for preventing the operation of said finder switch when a connection is extended to a line of a different character.
20. In a telephone exchange system, calling subscribers' lines, other subscribers' lines of different characters, connecting circuits and switches for establishing connections from said calling lines to said other lines, message registers associated with said calling lines respectively, register controlling devices, finder switches for said controlling devices respectively, for associating an idle one of said devices with a completed connection in order to cause the operation of the message register of the calling line, when a connection is extended to a line of one character and for preventing operation of a finder switch when a connection is extended to a line of a different character.

In witness whereof, I hereunto subscribe my name this 13th day of January, A. D. 1916.

ALBEN E. LUNDELL.
